UNITED STATES PATENT OFFICE.

CALVIN C. MILLER, OF SUMMIT HILL, PENNSYLVANIA.

TOY.

1,170,311.

Specification of Letters Patent.

Patented Feb. 1, 1916.

Application filed August 25, 1915. Serial No. 47,317.

To all whom it may concern:

Be it known that I, CALVIN C. MILLER, a citizen of the United States, residing at Summit Hill, in the county of Carbon and State of Pennsylvania, have invented certain new and useful Improvements in Toys, of which the following is a specification.

This invention relates to a toy of the spring motor type and the principal object 10 of the invention is to provide a toy representing two men grinding a knife at a grind stone, one man holding the knife and bringing it into engagement with the grind stone and the second man turning the grind 15 stone.

Another object of the invention is to provide the spring motor with improved means for oscillating a rocking lever connected with one arm of the figure holding the knife so that the arm will be caused to swing 20 up and down and bring the knife into and out of engagement with the grind stone.

Another object of the invention is to so 25 mount the figure turning the grind stone that the figure will swing from the hips as the arms move with the turning grind stone, the figure turning the stone being placed in a seated position.

Another object of the invention is to so 30 construct this toy that the same may be formed of sheet metal with the exception of the gear wheels, axles and pivot rods.

This invention is illustrated in the accompanying drawings, wherein:

Figure 1 is a view showing the toy in side elevation, Fig. 2 is a view similar to Fig. 1 looking from the opposite side of the toy, Fig. 3 is a view showing the toy in end elevation, and Fig. 4 is an enlarged perspective view of the lever forming part of 40 the toy and connected with the arms of the figure holding the knife by means of a draw rod.

The platform or base 10 is formed of 45 sheet metal and carries the table 11 which has its supporting legs 12 provided with teeth 13 connected with the platform. This platform also carries the frame 14 of the spring motor which is positioned adjacent the table 11 intermediate the length thereof.

The grind stone 15 is rigidly mounted upon the driven shaft 16 rotatably supported by the upper portion of frame 14 and is positioned over the table 11 with its lower portion extending through an opening formed in the table. The driven shaft car-

ries a relatively small gear 17 which gear meshes with a relatively large gear 18 carried by the shaft 19, the shaft 19 being in its turn provided with a relatively small gear 20 which meshes with the large gear 21 carried by shaft 22. The shaft 22 is also provided with a small gear 23 which meshes with the large gear 24 carried by the driving shaft 25, the driving shaft being provided with a spring 26 intermediate its length within the frame 14 and with a turning key 27 for winding the spring and with an arm 28 at its opposite end provided with fingers 29. It will thus be seen that the spring motor will be wound by means of key 27 and that when the key is released the motor will rotate the shaft 16 thus rotating the grind stone. It should also be noted that this grind stone may be provided with a 75 facing 30 of emery so that when in use sparks will be caused to be struck off.

The standing figure 31 has its arms 32 pivotally connected with the body portion by means of pin 33 and has one arm provided 80 with a tongue 34 with which the draw rod 35 is connected. This draw rod has its lower end bent to form a stem or pin 36 which passes through openings in the arms 37 of the lever or treadle 38, the lever being positioned beneath the arm 28 and pivotally mounted upon the rod 39 carried by the legs of the table and passing through the openings 40 in the treadle. It should be noted that the body portion of this figure 31 is inclined forwardly slightly to assume the natural position of a person grinding a knife 85 41 held in the hand of the figure. It should also be noted that as the driving shaft 25 rotates the fingers 29 of the arm 28 will engage the lever 38 and cause the lever to oscillate thus swinging the arm from the position shown in full lines in Figs. 1 and 2 to the position indicated by dotted lines in Fig. 1 thus causing the knife to be brought into 100 and out of engagement with the grind stone. The arms will of course have sufficient weight to normally retain the lever in a raised position and therefore after the lever has been depressed by one of the fingers 29 105 110 it will be raised until again depressed by the second finger. As the knife is brought into engagement with the revolving grind stone, sparks will be caused to slide from the emery coating thus giving a very good representation of a person grinding a knife.

The figure 42 which is shown in a seated

position to one side of the table 11 has its body portion pivotally connected with the legs 43 by means of pins 44 carried by the table and has its arms 45 pivotally connected 5 with the body portion by means of the pivot pin 46. These arms are extended in front of the figure and have the hands connected with the handle 47 of the grind stone and it will thus be seen that as the grind stone 10 rotates the arms of the seated figure will be moved in the manner natural to a person turning a grind stone, at the same time the body being caused to swing back and forth at the hips as would also be natural to a 15 person turning a grind stone.

When this toy is in use it is placed upon a convenient support such as a table or other stand and the spring motor is then wound by means of key 27. Upon releasing the key 20 the motor will begin to turn and the grind stone will be rotated thus causing the seated figure to go through the motion of turning the grind stone. At the same time the lever 25 will be actuated to swing the arms of the standing figure through the medium of draw rod 35 thus causing the standing figure to go through the motion of moving the knife into and out of engagement with the grind stone. This operation will be continued 30 until the spring of the motor has completely unwound. It has been stated that the figure, table, platform and motor frame will be formed from tin or other sheet metal stamped and bent to assume the proper 35 shape but it is obvious that the various elements could be formed of any suitable material such as being cut from wood or the like or it may be formed from cast metal or molded material.

40. What is claimed is:—

1. A toy comprising a support, a table carried by said support, a motor positioned upon said support adjacent said table and including a driving shaft extending beneath 45 the table and a driven shaft extending above the table, a figure placed in a seated position adjacent said table and provided with a pivotally mounted body portion and with pivotally mounted arms extending in front of 50 the body portion, a grind stone carried by said driven shaft and provided with a handle connected with the hands of the seated figure to impart motion to the figure as the grind stone rotates, a second figure placed in 55 a standing position adjacent said table and having its arms pivotally mounted and extending to hold an article above said grind stone, a lever pivotally mounted beneath said table and having its free end portion 60 extending toward said standing figure to one side thereof, a draw rod connecting the free end portion of said lever with the arms of said standing figure, and an arm carried by said driving shaft and provided with fingers 65 extending to engage said lever as said driv-

ing shaft rotates to oscillate the lever and cause the arms of the standing figure to be moved toward and away from said grind stone.

2. A toy of the character described including a support, a table carried by said support, a motor carried by said support and including a driving shaft and a driven shaft, a grind stone carried by said driven shaft, a figure carried by said support adjacent said 70 table and provided with pivotally mounted arms extending toward said grind stone, an ear extending from one of said arms adjacent the shoulder portion thereof, a lever extending beneath the table, and pivotally connected therewith, a rod connecting the outer end portion of said lever with the ear of said arm, and an arm carried by said driving shaft and provided with fingers for engaging said lever to oscillate the lever as 75 the driving shaft rotates and rock the arms of the figures toward and away from said grind stone.

3. A toy comprising a support, a table carried by said support, a motor provided 90 with a driving shaft and with a driven shaft, a grind stone carried by said driven shaft, a figure mounted upon said support adjacent said table and provided with pivotally mounted arms extending toward the 95 grind stone carried by said driven shaft, a lever connected with the arms of said figure, and means carried by said driving shaft for engaging said lever to rock the lever and move the arms of the figure toward and 100 away from said grind stone.

4. A toy comprising a support, a motor carried by said support and including a driven shaft and a driving shaft, a grind stone carried by said driven shaft, a figure 105 carried by said support and provided with pivotally mounted arms extending toward said grind stone, a lever, a rod connecting said lever with the arms of said figure, the weight of the arms normally holding the 110 lever in an elevated position, and means carried by the driving shaft of said motor for engaging said lever to move the same downwardly and swing the arms of the figure upwardly.

5. A toy comprising a support, a motor carried by said support and including a driving shaft and a driven shaft, a grind stone carried by said driven shaft, a figure positioned adjacent the grind stone and provided with pivotally mounted arms, and means actuated from said driving shaft to move the arms of said figure toward and away from the grind stone.

6. A toy comprising a support, a motor carried by said support and including a driving shaft and a driven shaft, a grind stone carried by said driven shaft, a figure positioned adjacent said grind stone and having its arms connected therewith, where-

by turning of the grind stone will move the figure to represent a person turning the grind stone, a second figure positioned adjacent the grind stone, means connected with the arms of the second figure for moving the arms toward and away from the grind stone, and means carried by said driving shaft to engage said last mentioned

means and actuate the same when said motor is in motion.

In testimony whereof I affix my signature in presence of two witnesses.

CALVIN C. MILLER.
